CAN SEPARATING DEVICE

Victor B. Evans, San Jose, Calif.

Application August 7, 1948, Serial No. 43,139

1 Claim. (Cl. 198—34)

1

Canned fruits and vegetables are frequently stored or shipped, in cases, unlabeled; it being necessary to subsequently de-case the cans for applying the labels. As de-cased, the cans are in longitudinal rows stacked one upon the other above a common support. These stacked rows must be separated into individually supported rows for feeding to the labeling machine, or the like.

This invention is, therefore, directed to, and it is an object to provide, a novel device for automatically and mechanically separating initially stacked longitudinal rows of cans into individual longitudinal rows supported independently of each other for subsequent handling.

A further object of the invention is to provide a can separating device, as above, wherein the initially stacked longitudinal rows of cans are shifted, upon simultaneous advance of the rows, in a manner to create spacing between the initially matchingly engaged ends of corresponding cans of said rows; such spacing then permitting the relative introduction of a separate support below each shifted upper row.

Another object of the invention is to provide a can separating device, which is designed so that the separation of the initially stacked rows of cans results, automatically, upon advance of said stacked rows through the device; the latter including a novel arrangement to relatively introduce a separate supporting plate between said rows whereby the latter are thereafter individually and independently supported.

A further object of the invention is to produce a simple, practical, and reliable can separating device, and one which will be exceedingly effective for the purpose for which it is designed.

These objects are accomplished by means of such structure and relative arrangement of parts as will fully appear by a perusal of the following specification and claim.

In the drawings:

Figure 1 is a fragmentary plan view of the device, as constructed to receive a single course of longitudinal, stacked rows of cans.

Figure 2 is a cross section on line 2—2 of Fig. 1.

Figure 3 is a cross section on line 3—3 of Fig. 1.

Figure 4 is a cross section on line 4—4 of Fig. 1.

Referring now more particularly to the characters of reference on the drawings, the device is here shown as constructed to handle a single course of initially stacked longitudinal rows of cans; there being a lower row, indicated generally at 1, and an upper row, indicated generally at 2.

2

The cans of the lower row 1 are each indicated at 3, while the cans of the upper row are each indicated at 4.

The single initially stacked longitudinal rows 5 and 2 of cans 3 and 4 are advanced by a pusher mechanism (not here shown) through a relatively deep trough, indicated generally at 5; such trough including a horizontal bottom or supporting plate 6 and upstanding transversely spaced side walls 7 and 8 extending lengthwise parallel to each other.

The course of initially stacked longitudinal rows 1 and 2 of cans 3 and 4 is fed into the trough 5 in the direction indicated by the arrow in Fig. 1.

The cans 3 of the lower row 1 are guided on opposite sides and adjacent the plate 6 by transversely spaced longitudinal guides 9. Similarly, the cans 4 of the upper row 2 run, at their lower ends between, and are guided by, transversely spaced longitudinal guides 10 affixed to the side walls 7 and 8 intermediate the top and bottom thereof. The longitudinal guides 10 are of such height, and so disposed, that they also are engaged by and guide the top portions of the cans 3 of the lower row 1.

As the initially stacked longitudinal rows of cans enter the device, the corresponding cans 3 and 4 in said rows engage at adjacent ends in matching relation, as at 11, in Fig. 2.

Another longitudinal guide 12 is affixed to the side wall 7 a considerable distance above the corresponding longitudinal guide 10, and in position to engage the adjacent sides of the cans 4 near the top of the same.

Intermediate the ends of the device, the longitudinal guide 12 is increased in width, i. e. laterally inwardly, and for a predetermined distance lengthwise of said device. This increase in width of the longitudinal guide 12 forms a longitudinal cam, indicated at 13.

As the initially stacked longitudinal rows of cans traverse the portion of the trough 5 corresponding to the longitudinal cam 13, the cans 4 of the upper row 2 are engaged by said cam 13 and tilted laterally, as in Fig. 3. The side wall 8 is relieved laterally outwardly at the top opposite the cam 13, and for substantially the same length, as at 14, to permit of unobstructed tilting of the cans 4 by said cam 13 in the manner previously described.

When the cam engaged cans 4 are tilted, there is a gap 15 formed between the lower end of each tilted can 4 and the corresponding can 3.

This gap is taken advantage of to permit of the

3

relative interposition of a separating and supporting plate 16 between the upper and lower rows of cans in the following manner:

The separating and supporting plate 16 is mounted between the side walls 7 and 8 directly below the longitudinal guides 10. The lead end of the separating and supporting plate 16 is formed with a diagonal edge 17 so that said plate 16 feathers out to a starting point 18 at the side wall 7 adjacent but ahead of the beginning of the cam 13 with respect to the direction of travel of the cans through the device.

Thus, as the initially stacked longitudinal rows 1 and 2 of cans 3 and 4 travel through the device, the cans 4 are tilted laterally when first engaged by the cam 13 and then continue forward, so tilted, for a certain distance. Soon after the cans 4 are tilted, and with their continued advance, the diagonal lead end portion of the separating and supporting plate 16 begins its relative entry between said tilted cans 4 and the corresponding cans 3; such entry being into the gap 15.

It will thus be recognized that by the time the tilted cans 4 escape the longitudinal cam 13 and re-erect in the trough 5, that said cans 4 are wholly supported by the separating and supporting plate 16 in spaced relation above the cans 3. See Figure 4.

The device is, therefore, operative, with the simple advance of initially stacked longitudinal rows of cans through the trough 5, to separate such longitudinal rows, and to individually support the same, for subsequent handling. From the outlet of the device the then individually and separately supported rows of cans can be fed by any convenient mechanism to the point where the cans of such row are to be processed, as to a labeling machine for the application of labels.

The device, while being very practical and effective for the intended purpose, nevertheless requires no moving parts and consequently has nothing to service or maintain.

In can de-casing operations, wherein a plurality of courses of stacked longitudinal rows of cans are involved with said courses in side by side relation, the above described device will be provided in a number corresponding to such courses with said devices in like side by side re-

5

lation. Thereafter all of the courses are advanced simultaneously through the corresponding separating device by a common pusher.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described the invention, the following is claimed as new and useful and upon which Letters Patent is desired:

A can separating device for a stack of cans including lower and upper cans initially in end to end engagement, the device comprising a longitudinal vertical-sided trough wider than the cans and in which the stack of cans is adapted to be advanced, longitudinal guide strips in the trough disposed to initially engage the lower cans at the top and the upper cans at the bottom and centralize the cans in the trough, and a longitudinal cam strip in the trough on one side thereof at a level to engage the upper cans adjacent the top; said cam strip being initially no wider than the corresponding guide strip and increasing in width to tilt the upper cans laterally for a certain length of the travel of the stack so as to cause a gap to be formed between the adjacent ends of the upper and lower cans on said side; there being a longitudinal support in the trough arranged at its leading end to enter said gap upon advance of the stack and to then fully receive and support the upper cans.

VICTOR B. EVANS.
